COMBINED LADLE AND STRAINER

Walter Schlessel, Lawrence, N.Y., assignor to Gessler Products Corporation, Jamaica, N.Y., a corporation of New York

Filed May 27, 1960, Ser. No. 60,768

Term of patent 14 years

(Cl. D44—29)

FIG. 2

FIG. 1 is a perspective view of a combined ladle and strainer showing my new design, and

FIG. 2 is a side elevational view thereof.

I claim:

The ornamental design for a combined ladle and strainer, as shown.
